UNITED STATES PATENT OFFICE.

ALFRED LEONARD NEWELL, OF PRESTBURY, ENGLAND.

SCALE, RULE, AND LIKE MEASURE OF LENGTH.

1,273,086.

Specification of Letters Patent. Patented July 16, 1918.

Application filed April 17, 1918. Serial No. 229,135.

To all whom it may concern:

Be it known that I, ALFRED LEONARD NEWELL, a subject of the King of Great Britain and Ireland, and a resident of 5 Prestbury, in the county of Chester, England, have invented certain new and useful Improvements in or Relating to Scales, Rules, and like Measures of Length, of which the following is a specification.

10 This invention relates to scales, rules and like measures of length (hereinafter for convenience referred to as scales) and has for its object to provide a scale which can be cheaply produced and is especially applicable as an advertising medium.

A scale in accordance with this invention consists of a strip of thin sheet metal of suitable length and width and a stiffening strip of cardboard, wood or other suitable 20 material of lesser width around the longitudinal edges of which the sides of the metal strip are bent so that their edges do not meet at the back.

In the accompanying drawing, Figures 1 and 2 are fragmentary perspective views of 25 one construction of scale or rule in accordance with the invention, Figs. 3 and 4, respectively, are like views of two further constructions and Fig. 5 is a similar view 30 of the metal strip before bending.

Referring to the drawing, *a* is a strip of thin metal of appropriate width and marked with the required divisions and *b* is a strip of stiffening material of lesser 35 width around the longitudinal edges of which the strip *a* is bent so that the edges *a* thereof do not meet. In Figs. 1 and 2 the stiffening strip *b* is of cardboard or the like and in Figs. 3 and 4 the strips are of 40 wood.

At the front the edges of the scale are preferably beveled and at the back the scale is preferably correspondingly or otherwise concaved. This may be effected when the 45 stiffening strip is of cardboard or like material by bending the metal and stiffening strips longitudinally as at *c*, Figs. 1 and 2, at a suitable distance from the edges of the scale, while if the stiffening strip is of wood 50 or other material which will not bend, it may be effected by shaping the stiffening strip *b* with beveled edges at the front and a concavity *b* at the back, as in Fig. 3. In

some cases, however, the back of the scale may be flat, as in Fig. 4.

55 The required divisions are preferably printed or otherwise marked on the metal strip *a* before the latter is attached to the stiffening strip *b* and the markings are preferably of such transverse length, as 60 shown in Fig. 5, that on the bending of the strip along the dotted lines *d*, they also appear on the back of the scale, as illustrated in Figs. 1 and 2.

When the scale is used as an advertising 65 medium the advertisement may be printed or otherwise provided on the back of the stiffening piece *b* or on a separate strip of paper or other material *e* (Fig. 4) secured thereto by an adhesive or by the bent or 70 turned-over sides of the metal strip *a*. The advertisement will be prevented from coming into contact with any surface on which the scale is laid or rests and being thereby 75 damaged by reason of its lying within the concavity of the back of the scale or between the bent or turned-over sides of the metal strip.

What I claim as my invention and desire 80 to secure by Letters Patent is:—

1. A scale, rule or like measure of length comprising a strip of thin metal of suitable length and width and marked with the required divisions, and a stiffening strip of lesser width around the longitudinal edges 85 of which the sides of the metal strip are bent so that their edges do not meet at the back, said metal strip being permanently attached to said stiffening strip.

2. A scale, rule or like measure of length 90 comprising a stiffening strip and a thin metal strip of greater width than said stiffening strip and bent around the longitudinal edges thereof so that its side edges do not meet at the back, said metal strip 95 having the required divisions on both sides of both longitudinal edges and being permanently attached to said stiffening strip.

3. A scale, rule or like measure of length comprising a stiffening strip concaved on 100 one side and flat on the other side and having its longitudinal edges beveled, and a thin metal strip of greater width than said stiffening strip and bent around the longitudinal edges thereof so that its side edges do 105 not meet at the concaved side, said metal

strip being permanently attached to said stiffening strip.

4. As a new article of manufacture, a ruler comprising a stiffening strip flat on one side and concave on the other and having longitudinal beveled edges, and a thin metallic strip bent around the edges and flat side of said stiffening strip and permanently at-

tached thereto, said metallic strip being provided on both sides of both edges with graduations of measure, substantially as described. 10

In witness whereof I have hereunto set my hand.

ALFRED LEONARD NEWELL.
